UNITED STATES PATENT OFFICE.

GUSTAVUS A. SCHLECHTER, OF READING, PENNSYLVANIA.

DESIGN FOR A MEDAL.

SPECIFICATION forming part of Design No. 20,970, dated July 28, 1891.

Application filed June 19, 1891. Serial No. 396,842. Term of patent 3½ years.

To all whom it may concern:

Be it known that I, GUSTAVUS A. SCHLECHTER, a citizen of the United States, residing at Reading, in the county of Berks, State of Pennsylvania, have invented a certain new and original Design for a Medal, of which the following is a specification.

The accompanying drawing illustrates my design, which consists in a circular form of medal having the special ornamentation shown on one of its faces.

The leading feature of this ornamentation consists of the representation of a man's figure B in the foreground, loosely wrapped in a military cloak, with uncovered head and having one knee resting upon the rough

frozen ground. In the near background is a tree A, and an army-tent C, with flying flag, is also distinctly seen. Above this picture and near the circular edge of the medal is a space D, on which may appear any suitable lettering.

What I claim is—

The design for a medal having the shape and ornamentation as herein described and shown in the drawing.

In testimony whereof I affix my signature in presence of two witnesses.

GUSTAVUS A. SCHLECHTER.
